UNITED STATES PATENT OFFICE.

WINFIELD E. HINSDALE, OF NEW YORK, N. Y.

URINAL.

SPECIFICATION forming part of Letters Patent No. 650,897, dated June 5, 1900.

Application filed October 7, 1899. Serial No. 732,973. (No model.)

To all whom it may concern:

Be it known that I, WINFIELD E. HINSDALE, a citizen of the United States, residing at New York, borough of Manhattan, county of New York, and State of New York, have made a new and useful Invention in Urinals, of which the following is a specification.

My invention is directed particularly to improvements in urinals adapted to be flushed by water admitted to the bowl thereof and passing therethrough in the usual manner; and its object is to devise a urinal of such a nature that it may be easily connected to and disconnected from the partition or wall of a toilet-room by the inlet and outlet fittings and in such manner that the connection between the urinal-bowl and the outlet-fitting shall always be beneath a water seal and of such a nature that there will be no possibility of the fitting becoming clogged or choked by any deposit of foreign matter.

Prior to my invention it has been the custom to connect urinals directly to partitions or walls of toilet-rooms with inlet and outlet connections in such manner that the connections presented large metal surfaces for the oxidizing action of such materials as are always present in such rooms. In other existing and more modern styles of urinals it is customary to place all of the water connections out of sight and behind the supporting partition or wall. In such cases the urinals are fastened to the partitions—usually of marble or slate—before placing them finally in position; but such a construction makes it necessary, in the event of the breakage of any parts of the urinal, to take down the entire partition in order to reach the connections. Still other types of urinals have been constructed and are now in general use in which the bowl of the urinal is made to hold a body of water and is usually constructed of a single piece of earthenware in order to provide room for the water-passages; but such structures are necessarily bulky and therefore occupy or utilize much valuable space, and my invention is designed to overcome the objectionable features attributable to the same. I construct my novel form of urinal of a single piece of glazed earthenware, the

top of which is provided with inlet and outlet openings, and an inlet-orifice is placed inside of the rim, and the rear or flange face of the inlet-opening is substantially in line with the back of the urinal - bowl. The outlet-opening is located directly in the bottom of the pan or bowl, and its outer surface or end is in a plane parallel with the corresponding surface of the inlet-opening, a flange being provided around said opening, through which is drilled, preferably, three holes for the purpose of receiving screws or bolts for securing the urinal in place. The joint between the outlet-opening at the bottom of the bowl and the outlet-fitting is formed by flanges, between which is located a rubber packing-ring, the arrangement being such that when the two are joined together with the sealing-packing there is formed a continuous outlet without any obstruction, the inner surface of said joint and packing-ring being wholly immersed in a water seal. A single screw or bolt is provided at the upper end of the urinal for securing it in place, so that the entire urinal is secured directly to the partition or wall by four screws or bolts extending into the metallic parts of the fixture, which are permanently secured to the wall. I also construct the urinal with a groove or flange extending entirely beneath the bowl for the purpose of receiving a protecting and concealing shield, made also of earthenware, the entire arrangement being such that when the urinal is in position only a single metallic sustaining-screw head—to wit, that in the top of the urinal—is visible.

For a full and clear understanding of my invention, such as will enable others skilled in the art to construct and use the same, reference is had to the accompanying drawing, which is a longitudinal sectional view taken through the body of my improved urinal, illustrating its application or use in connection with the siphon type of flushing devices by which urinals are flushed from the bottom of the bowl and a perforated filling-rim at the top and sides of the bowl.

Referring now to the drawing in detail, M represents a marble partition or wall to which the urinal is secured, said partition having

two openings therein, the upper one for receiving the inlet-fitting and the lower one for receiving the outlet-fitting.

II represents the inlet-fitting, which consists of a short piece of metallic tubing having an opening at one end for discharging water into the urinal and provided with a flange near its middle and a screw-thread about its other end for securing it in position in the marble or slate partition or wall M by a nut t.

P represents the inlet-pipe, which is secured to the inlet-fitting II by a screw-threaded sleeve N and screw-collar K', said parts being in turn secured to the inlet-fitting II by a sleeve K.

II' is the outlet-fitting, of gooseneck pattern, such as is ordinarily used in connection with siphon flushing devices, F³ being a flange for securing said outlet-fitting directly to the marble partition or wall M by one or more screw-bolts b².

t² is the flushing-inlet, which is connected by the pipe P' and screw-collar K² to the screw-threaded sleeve N and inlet-pipe P, this arrangement being of well-known form.

G is the partition or wall in the fitting II', which gives to said fitting the siphon-like structure. The inner end of the fitting II' is provided with a face-flange F', which has the necessary groove for receiving a rubber packing-ring R between it and the lower outlet or discharge fitting of the urinal, said flange being provided with, preferably, three screw-holes for receiving screw-bolts b' and securing the urinal at its lower end, the arrangement being such that the interior diameters of the outlet of the bowl and the adjoining outlet-fitting when held together by the screw-bolts with the intervening rubber packing-ring offer no obstruction to the passage of foreign matter, it being also noted that this joint is located in a water seal between the base of the bowl and the partition-wall G.

U constitutes the urinal, of bowl pattern, provided with inlet-orifices i i and an upper rim J, which is hollow, as shown, and is provided with a flange or rim F², the face of which is in a plane parallel with the face of the outlet flange F, the arrangement being such that when the urinal-bowl is put into position these two face-flanges F and F² will rest, respectively, against the corresponding face-flange F' of the outlet-fitting II' and the surface of the marble partition or wall M, the orifice-opening S in the rim J being located around the inlet-fitting II, which is screw-threaded, as shown, for the purpose of re-

ceiving a cap-screw b, said cap-screw and the three or more screws b' constituting the sole means of securing the urinal in place.

R² and R³ are rubber packing-rings located between the cap-screw b and the inner and outer ends of the orifice or opening through the upper rim of the urinal for rendering the joints water and gas tight.

G' is a downwardly-extending ledge running entirely around the bottom of the earthenware bowl of the urinal U and adapted to receive and conceal the upper edge of an earthenware shield B, the lower edge of which rests against the face of the partition or wall M at a point below all of the parts of the urinal, said shield being held in place in any preferred manner and constituting a protecting shield or casing to all of the parts.

Having thus described my invention, what I claim, and desire to secure by Letters Patent of the United States, is—

1. An earthenware urinal having supporting face-flanges F, F²; in combination with a supporting-partition and an outlet-fitting having a flange F', the first-named flanges being adapted to rest against the supporting-partition and the flange F' respectively, and an inlet-fitting extending through an orifice in the upper flange; together with a sealing-ring located between the outlet of the bowl and the outlet-fitting, the joint between the outlet of the bowl, the outlet-fitting, and the sealing-ring being located in a water seal, and all of said parts secured together by screw-bolts, substantially as described.

2. An earthenware urinal having supporting face-flanges F, F²; in combination with a supporting-partition and an outlet-fitting having a flange F', the first-named flanges being adapted to rest against the supporting-partition and the flange F' respectively; a sealing-ring between the outlet of the bowl and the outlet-fitting, the interior diameters of said sealing-ring and the adjacent fittings, when secured together, being the same and the joint made thereby located always beneath a water seal; together with bolts for securing said parts together and an earthenware shield B located beneath the bowl and adapted to conceal the exposed parts of the joint and outlet-fitting, substantially as described.

In testimony whereof I have hereunto subscribed my name this 4th day of October, 1899.

WINFIELD E. HINSDALE.
